MINIATURE POWER ACTUATED MULTIPLE PUNCH FOR IMPLANTING HAIR

Frank A. Bellantoni, 101 Helena Ave.,
Yonkers, N.Y. 10710

Filed Apr. 6, 1970, Ser. No. 22,264

Term of patent 14 years

Int. Cl. D24—03

U.S. Cl. D83—12

Fig. 1.

Fig. 2.

Fig. 4.

Fig. 5.

Fig. 5.

FIG. 1 is a perspective view of the miniature power actuated multiple punch for implanting hair embodying the features of my new design;

FIG. 2 is a top plan view thereof,

FIG. 3 is a rear elevational view thereof,

FIG. 4 is a side elevational view thereof, and

FIG. 5 is a fragmentary enlarged perspective view showing the implanting punch.

I claim:

The ornamental design for a miniature power actuated multiple punch for implanting hair, substantially as shown.
